(57) **CLAIM**

An ornamental design for a bracket of a hydraulic power steering kit, as shown and described.

DESCRIPTION

FIG. 1 is a perspective view of a design of a bracket of a hydraulic power steering kit for a Ford 5.0L Coyote engine; FIG. 2 is a front view of the design of the bracket of a hydraulic power steering kit;

FIG. 3 is a rear view of the design of the bracket of a hydraulic power steering kit;

FIG. 4 is a top view of the design of the bracket of a hydraulic power steering kit;

FIG. 5 is a bottom view of the design of the bracket of a hydraulic power steering kit;

FIG. 6 is a first side view of the design of the bracket of a hydraulic power steering kit;

FIG. 7 is a second side view of the design of the bracket of a hydraulic power steering kit; and,

FIG. 8 is a perspective view of the design of the bracket of a hydraulic power steering kit with attached hydraulic power steering drive components.
